UNITED STATES PATENT OFFICE.

PIROSKA GÁSPÁR, OF BRIDGEPORT, CONNECTICUT.

SPRING-HEEL FOR BOOTS AND SHOES.

1,081,734.

Specification of Letters Patent.

Patented Dec. 16, 1913.

Application filed October 1, 1913. Serial No. 792,709.

To all whom it may concern:

Be it known that I, PIROSKA GÁSPÁR, a subject of the King of Hungary, residing at Bridgeport, in the county of Fairfield 5 and State of Connecticut, have invented certain new and useful Improvements in Spring-Heels for Boots and Shoes, of which the following is a specification.

This invention relates to spring heels for 10 boots and shoes.

The object of the invention is to provide a heel which shall be neat in appearance, thoroughly efficient in operation in absorbing jars, and which may be made and applied to the heel of any custom-made shoe 15 without requiring any change in its structure and arrangement.

With the above and other objects in view, as will appear as the nature of the invention 20 is better understood, the same consists in the novel construction and combination of parts of a spring heel, as will be hereinafter fully described and claimed.

In the accompanying drawing forming a 25 part of this specification, and in which like characters of reference indicate corresponding parts: Figure 1 is a perspective view of a shoe equipped with the heel of the present invention. Fig. 2 is a vertical longitudinal section through the heel, showing the manner of connecting the elements of the spring member, and also the manner in 30 which the spring element is held in position. Fig. 3 is a horizontal sectional view taken 35 on the line 3—3, Fig. 2, and looking in the direction of the arrow thereon. Fig. 4 is a perspective fragmentary detail view, partly in section, showing the relative arrangement of the parts of the cushion 40 member.

While the invention is shown in this instance as applied to a man's shoe, it is to be understood that it is equally adaptable for use in connection with any kind of foot 45 gear, and as this will be readily understood, any extended illustration is deemed unnecessary.

Referring to the drawings, 1 designates the counter of the shoe, which as usual, is 50 secured between the sole 2 and liner 3. The heel may consist of any desired number of lifts, those herein shown being designated 4, 5, 6, 7, 8, 9, and 10. The lift 4 as usual, is secured to the sole, and is provided at its 55 center with a depression 11, while the lift 5 is provided with a rectangular opening 12

in which is seated a plate 13, the same being held in place by screws or nails 14. At the center of the plate is a threaded orifice 15 that is designed to be engaged by a threaded 60 plug 16 that extends through a circular orifice 16* in the lift 6 and is provided with a transverse orifice to receive one end 17 of a coiled spring 18, the other end 19 of which projects through an orifice formed 65 in a complementary plug 20 that engages the threaded orifice arranged at the center of a second rectangular plate 21 that is seated in the lift 8, the plug 20 projecting through a circular opening 22 in the lift 7. It will 70 be noted that both of the openings 16 and 22 are of less diameter than the plates 12 and 21, so that the latter will be held firmly positioned between the adjacent lifts 4, 6, 7 and 9. The lift 9 is provided with a central depression 23, which, in conjunction 75 with the like depression 11 in the lift 4, is designed to permit of an extended range of adjustment of the two plugs 16 and 20 so as to increase or diminish the resistance to 80 depression of the lower or ground-engaging member of the heel, thus to adapt the improvements to persons of different weights.

Inclosing the lower member of the heel, which is composed of the lifts 7—10, is a 85 shield 24, which may be made of any suitable material, preferably of leather, and is held assembled with the lifts 8—10 by nails or screws 25. This shield extends a sufficient distance above the lift 7 to receive the 90 lower portion of the upper heel member consisting of the lifts 4—6, and permits a telescoping action between the two members, and guides the lower member relative to the upper one as the heel is alternately 95 depressed and released in use.

In combining the cushioning member with the heel members, the plate 5 is first seated, and secured in place by the nails or screws 12, after which the plug 16 is turned to its 100 seat, and the lift 6 secured to the lift 5. The plate 21 is then seated in the lift 8, and the lift 7 secured in place after which the lower member is turned to cause the plug 20 to seat in the threaded opening in the plate 105 21. The parts being thus assembled, the lift 10 is now secured in position, and finally the shield 24 is combined with the heel.

In use, the weight of the user will cause the lower member to telescope around the 110 upper member and thus absorb all jars and shocks, and as before stated, the cushioning

member may be adjusted so as to cause it to meet any condition which may arise in use.

What I claim as new is:—

5 A heel comprising an upper and a lower member, a plate arranged in each of the members and having a threaded orifice, plugs engaging the orifices, each plug having a transverse opening, a coiled spring having its terminals passed through the said-

openings, and a shield carried by the lower member and arranged partially to house the upper member.

In testimony whereof I affix my signature in presence of two witnesses.

PIROSKA GÁSPÁR.
